UNITED STATES PATENT OFFICE

1,988,321

ELECTRIC SOCKET

Francis C. Kollath, Chicago, and Daniel Woodhead, Evanston, Ill.

Application July 15, 1929, Serial No. 378,357

1 Claim. (Cl. 173—358)

This invention relates to electric sockets in general and particularly to an electric socket which is removably arranged within a casing.

The object of the invention is to provide a new and improved socket which can be removably arranged inside of a flexible rubber casing.

A further object is to provide a socket having improved means for preventing tension exerted on the conductors from being transmitted to the socket terminals.

A further object is to provide a socket member having clamping means arranged thereon for clamping a part of the socket member to the electric conductors to which the socket is connected.

A still further object is to provide a socket having a flexible rubber casing arranged inside of a guard handle which detachably supports a lamp guard.

Other objects and advantages will appear through the progress of the specification.

The invention comprises in general a socket member having an insulated disk which is of greater diameter than the general diameter of the socket. The socket fits into a flexible rubber casing which has an annular groove into which the insulated disk fits. The interfitting engagement of the disk with the annular groove holds the socket in proper operable position relative to the casing.

The outer end of the casing is provided with a longitudinal passage through which the conductors leading to the socket terminals pass. Part of this passage is provided with ribs or teeth which bite into the conductor when a clamp which is arranged about the forward end of the casing is tightened in position. The assembled socket and casing are adapted to fit inside of a handle guard, and a lamp guard is removably attached to the guard handle.

The accompanying drawing illustrates a selected embodiment of the invention and the views therein are as follows:

Fig. 1 is a detail sectional view of a lamp and guard handle having the improved socket and casing arranged therein.

Fig. 2 is a detail sectional view showing the general arrangement and construction of the parts.

Referring to the drawing, 5 designates a socket member generally having the usual threaded shell or socket member 6 to receive an electric lamp 7 or other member, such as a plug (not shown). The shell 6 is connected to a circular insulated member or disk 8, and terminals 9 and

10 are fastened to the disk and have electrical connection with the shell 6 and contact 11 respectively in the usual manner.

The socket member 5 is made of flexible rubber and has a compartment or chamber 13 into which the socket fits. This member 5 which is made of flexible rubber, is resilient and comparatively soft so that it may bend and stretch within reasonable limits. An annular groove 14 is provided on the inside of the member 5 to receive the disk 8 which is normally larger in diameter than the general inside diameter of the socket member 5. When the socket is inserted in the casing the disk will engage the groove and hold the socket in normal fixed or placed position.

The forward end of the socket member 5, to the left, Figs. 1 and 2, is tapered at 15 and has a cylindrical end 16 which receives a clamp 17. A longitudinal passage 18 is provided in the forward end of the socket member to accommodate the electric conductors 19 which are electrically connected to the terminals 9 and 10, as clearly shown in Fig. 2.

The clamp 17 is preferably composed of two parts 20 and 21 which are maintained in operative relationship by tightening means 22.

The inside of the longitudinal passage or bore 18 is provided with teeth or ribs 23 which bite into the sheath surrounding the conductors 19 when the clamp 17 is tightened in place. Any tension which may be exerted on the conductors or the sheath is transmitted directly to the socket member and not on the terminals 9 and 10.

If desired, the socket member 5 may be arranged in a lamp and guard handle of the type shown and described in Patent 1,507,742, granted September 9, 1924. If the present socket member is to be used in connection with a lamp and guard handle of the type mentioned in the aforementioned patent, an annular groove 24 may be provided on the outside of the socket member to receive the annular collar 25 which is arranged on the inside of the guard handle 26 to hold the socket member 5 in place in the guard handle.

The chamber 27 of the guard handle receives the socket member 5 and has a shoulder 28 against which the forward end of the socket member 5 or the clamp 17 may abut when tension is exerted on the conductors. The guard also has a longitudinal passage 29 extending through its handle 30 and communicates with the chamber 27 to receive the conductors 19. The conductors 19 are enclosed in a flexible insulated sheath or cable as shown in the drawing.

A lamp guard 31 is provided with a clamp 32

which nests in the annular groove 33 in the guard handle, as shown in the drawing and which is clearly shown and described in the previously mentioned patent.

5 The invention provides a socket member 5 detachably arranged inside of a flexible rubber guard handle and is maintained from displacement when mounted in this guard handle.

10 The teeth on the inside of the longitudinal passage and the exterior clamp provides positive means for preventing any strain from being exerted on the socket terminals. The entire socket member and its cooperating parts are compact and can be readily arranged inside of a guard 15 handle. The guard handle is provided with means for detachably securing the socket member in position in the guard handle, and the guard handle is provided with means for detachably supporting a lamp guard.

20 Changes may be made in the form, construc-

tion, and arrangement of the parts without departing from the spirit of the invention or sacrificing any of its advantages, and the right is hereby reserved to make all such changes as fairly fall within the scope of the following claim. 5

The invention is hereby claimed as follows:

A socket member comprising a casing of resilient material having a groove therein, a metal screw threaded shell arranged in said casing, a disk fastened to said shell engageable with said groove for holding said shell in said casing, said casing having a longitudinal passage therein, a conductor cable extending through said passage and electrically connected to said shell, a clamp about a part of said casing, and ribs integrally 10 formed on said casing and arranged on the inside of said passage for biting into said conductor cable when said clamp is tightened. 15
